AUTOMATIC CONTROL AND SAFETY COVER
FOR EXTRACTORSOscar W. Johnson, Rochester, N. Y., assignor to
The American Laundry Machinery Company,
Cincinnati, Ohio, a corporation of Ohio

Application August 24, 1946, Serial No. 692,876

7 Claims. (Cl. 192—136)

1

This invention relates to centrifugal extractors such as are used for extracting liquid detergent, e. g., soap solution or a volatile solvent, from garments or fabrics washed or cleaned in a laundry or dry cleaning plant. The invention has more particular relation to the control mechanism including the safety cover lock.

One object of the invention is to provide an extractor equipped with an improved pneumatic electric control system, operation of which closes and locks the safety cover, starts the driving motor, times the extracting operation, opens the motor circuit at the conclusion of the extracting operation, applies the brake to bring the basket to rest, signals the operator that the extracting operation is finished, and, upon initiation by the operator, opens the cover to enable the extracted load to be withdrawn and replaced by a fresh load.

Another object is to provide an improved control system in which the cover cannot be opened or raised while the basket is rotating; in which it is impossible to start the motor while the cover is open or while the brake is applied; but in which, upon emergency, and before the lapse of the predetermined time period, it is always possible to stop the motor and release the cover.

Further objects of the invention in part are obvious and in part will appear more in detail hereinafter.

In the drawings, Fig. 1 represents, schematically, one arrangement of control mechanism embodying the invention, the parts being shown in positions assumed when the extractor basket is at rest, with brake applied and cover closed; Fig. 2 is a longitudinal sectional elevation through the cover operating servomotor;

Fig. 3 is a detail cross section on the line 3—3, Fig. 2;

Fig. 4 is a detail view of the brake operating mechanism, corresponding to Fig. 1, showing the brake applied, but with the basket still in motion;

Fig. 5 is a similar view, showing the brake parts in their positions when the extractor is running, and also when the basket is at rest with the brake released and the cover raised; and

Fig. 6 is a longitudinal sectional elevation through one of the pneumatic control valves.

The extractor itself forms no part of the invention, except as background for or as a part of, the present safety control system. It therefore may be of any suitable form and used for any desired purpose and has been illustrated conventionally and only to such extent as is necessary or desirable. It comprises the usual curb 10,

2

provided with a cover 11 hinged at 12, and in which curb rotates the foraminous basket 13 indicated by the dot-dash lines in Figs. 1, 4 and 5, said basket being mounted upon a shaft 14 driven by motor 15 (Fig. 1) and provided with a brake drum 16, with which cooperates a flexible brake band 17.

Brake band 17 has one end connected at 18 to a lever 19, pivoted at 20 to a fixed support, and its opposite end provided with the usual abutment 21 through which passes a link 22 on which is an adjustable compression spring 23, the other end of the link being connected to one arm of a bell crank lever 24, pivoted upon lever 19 at 24a, the other arm of which is connected to the piston rod 25 of brake band operating servomotor 26, also pivoted at 20 on the stationary support.

Lever 19 is biased toward a stationary supporting bracket 27 by a strong compression spring 28, as in Fig. 1, but under certain conditions moves away from said bracket to the position shown in Fig. 4. By such motion, to and fro, as well as by the motion of bell crank 24 and a roller 29 carried thereby, two electric switches, S1, S2, are actuated, as will later appear.

S2 represents a normally open manually operable push button switch mounted upon a control panel 33. This also supports a manually adjustable clock operated timing shaft 34 having a setting knob 35 and time indicating dial 36, the shaft being provided with a cam disc 37, cooperating with roller 38 on lever 39, biased by spring 40, for actuating the stem 41 of a control valve 42.

Upon the same panel 33 is mounted a similar control valve 43, the stem 44 of which is actuated by one arm 45 of a pivoted lever, biased by a spring 46. A second arm 47 of said lever cooperates, for latching purposes, with a pivoted latch lever 48, biased by spring 49 and provided with a core or armature 50 actuated by coil 51. A third arm 52 of said lever cooperates with the rod 53 of a servomotor 54.

Control valves 42, 43 are alike and of the form shown in Fig. 6, which illustrates valve 43. Each valve comprises a casing having a supply connection at 55, an exhaust connection or outlet 56, and a discharge connection 56a, the stem carrying an inlet valve member 57 and an exhaust valve member 58 biased toward exhaust position by spring 59.

Mounted to swing with the hinged cover 11 is an operating lever arm 60 (Fig. 1) having a cam portion 61 which operates a small pivoted lever 62, which in turn actuates a fourth electric

switch S₄. The free end of lever arm 60 is pivotally connected to the piston rod 63 of cover operating servomotor 64, pivoted on a fixed support at 65. As shown in Fig. 2, the piston 66 of this motor travels in a chamber 67 communicating above the piston, by way of adjustable needle valve 68 and larger check valve 69, with the inlet connection at 70, and having an outlet at 71. Said chamber, below or on the opposite side of the piston, communicates with another supply connection by way of needle valve 72, and inlet 72a. Here, also, the piston rod is provided with a tapered extension locking head 73 having an annular shoulder 74 cooperating with a latch bolt 75 connected to piston 76 working in chamber 77. The bolt is flattened on one side, to provide air channel 78, while its opposite or outer end portion carries retracting spring 79 and an operating head 80 outside of the casing accessible for manual operation.

The operation is as follows:

As will later appear, at the conclusion of each extracting operation, the parts come to rest in the positions shown in Fig. 5. Main switch 103 is open; the cover is open; the brake is released; valve 42 is closed; valve 43 is open; switch S₁ is closed; switch S₂ is open. The pressure supplied by valve 43 effective through cylinder 64 to cylinder 26, maintains the brake released.

Let us assume that all parts are at rest, ready for an extracting operation.

The operator unloads and reloads the basket.

An extracting operation is initiated by manually setting the timing device. The hand is applied to the knob 35, by means of which shaft 34 is rotated to any desired amount, as indicated on the dial 36, for the desired period of extraction. The rotation of shaft 34 turns lever 39 clockwise in Fig. 1, by causing roller 38 to ride up out of the cam recess in which it is shown seated, to a higher point of the cam, and the oscillation of lever 39, against the bias of its spring 40 elevates the stem and valve members of control valve 42, thereby opening its inlet valve member and closing its exhaust valve member.

Fluid pressure, such as air pressure, flows from a suitable source (not shown), by way of pipe 90, valve 42, and pipe 91, to the upper portion of chamber 67 of servomotor 64, by pipe 104 to motor 54, and, when piston 66 passes outlet 71, by pipe 92 to the chamber of servomotor 26. The piston 66 of servomotor 64 moves down to locked position, as shown in Fig. 2, thereby closing the cover and locking it closed. Cover closing motion closes switch S₄.

Closing of switch S₄ energizes a circuit as follows:

From L₁ by wire 82 to the junction 98, through an actuating coil 99, wire 100, switch S₁ and wire 101 to the junction 87, and thence back to L₃ by wire 88, switch S₄ and wire 89 to L₃. Energization of coil 99 moves over its armature 102, thereby closing, and maintaining closed, the main contactor switch 103, completing the connection of the leads L₁, L₂, L₃ to motor 15, and energizing said motor. As a result the motor immediately starts to rotate the basket and proceed with the extracting operation.

Fluid pressure transmitted through conduit 91 in the manner described, is also effective, through pipe 104, in servomotor 54, the rod of which moves the three armed lever 45, 47, 52 against its biasing spring 46, to the position shown in Fig. 1, in which it is latched by lever 48. Therefore, in control valve 43 the inlet valve member is closed and

the exhaust valve member is open, thus evacuating any pressure from chamber 67 below piston 66.

While the parts are in this position, i. e., when the extractor is running and performing its intended duty, the normally open push button switch S₃, which is in a circuit to be later described in detail, is ineffective, because that circuit includes the now open switch S₂. It is therefore impossible, as will appear, to open the cover of the extractor, by manipulation of switch S₃, while the extractor basket is running.

The extracting operation proceeds until the timing mechanism, by operation of its clock or other device for the purpose, returns to its original position shown in Fig. 1, thereby permitting roller 38 to enter the recess in the cam 37. Such operation of lever 39 moves the valve parts of control valve 42 to the position shown in Fig. 6, closing the inlet valve and opening the exhaust valve. This evacuates all pressure from the servomotors 26, 64 and 54.

Spring 106 in servomotor 26 thereupon retracts the piston of that servomotor, moving the parts from the position shown in Fig. 5 first to the position shown in Fig. 1, and applying the brake. Also, opening of switch S₁ deenergizes main contactor coil 99 so that the main motor switch 103 opens and the motor is deenergized, the basket gradually coming to rest. With power cut off and the brake applied, the momentum of the basket, effective upon the brake, moves lever 19 to the position shown in Fig. 4, swinging it away to the left from the supporting bracket 27, against the force of biasing spring 28. But switch S₂ remains open. Thus the signal light 81 remains deenergized. But ultimately, when the basket comes to rest, the reactionary back lash, plus the force of spring 28, returns the brake arm assembly, including lever 19 and its associated parts, back to the position shown in Fig. 1, so that roller 29 moves finger 93 to such position as to close switch S₂. Actually, motion of lever 24 to apply the brake and swinging motion of lever 19 to the left occur simultaneously, although described separately above.

Closing of switch S₂ completes a circuit as follows:

From L₁ by wire 82 to the junction 83, wire 84, lamp 81, wire 85, switch S₂, wire 86, to the junction 87, wire 88, switch S₄, and wire 89 to L₃. The lamp 81 therefore is lighted and notifies the operator that the extracting operation has been finished and that the basket has come to rest.

Closing of switch S₂ also renders effective that part of the circuit which includes push button switch S₃ (normally open), as follows: From L₁ by wire 82 to the junction 83, thence by wire 107, coil 51, wire 108, switch S₃ (still open) wire 109, wire 85, switch S₂ and wire 86 to the junction 87, and thence back to L₃ by wire 88, switch S₄ and wire 89, as before.

The operator now manually closes switch S₃, thereby energizing coil 51, which attracts the armature 50 associated with that coil, moving lever 48 in the counterclockwise direction Fig. 1, out of the possible path of movement of lever arm 47. The effect is to release lever arm 47 for return movement by its biasing spring in the counterclockwise direction, the arm 45 of said lever elevating the rod or control valve 43 and opening its inlet valve and closing its exhaust valve.

Fluid pressure now flows from the pipe 90 through valve 43 and by pipe 110 to that part of

chamber 67 beneath piston 66. The piston however is still locked down by the bolt 75. However, fluid pressure entering chamber 67 from inlet 72a flows by the passage 78 to the inner face of piston 76, thereby moving said piston to the right, Fig. 2, against its spring 79, and also moving the locking bolt 75 out of engagement with the locking abutment 74. As a consequence, the pressure in the lower part of chamber 67 now becomes effective, and elevates piston 66, which opens the extractor cover, the motion being somewhat retarded due to the restriction of needle valve 72.

As the cover rises, the cam 61 becomes effective upon lever 62, to depress the same and open switches S₄, thus opening the return path of L₃, by wire 88 from the junction 87, thereby deenergizing signal lamp 81. When piston 66 rises beyond the outlet pipe 71, pressure again flows through conduit 92 to the servomotor 26, thereby releasing the brake. The basket load is now removed and is replaced with a fresh load. The cycle of operations has been completed, and the extractor is ready for another operation.

As before stated, when the extractor is in operation it is impossible to open the cover by actuation of the ordinary means provided for that purpose, to wit, normally open push button switch S₃, because that part of the circuit which includes that switch is ineffective by reason of the fact that switch S₂ is open. However, it is possible, even when the extractor is running, to stop it and open the cover. This is done by manually returning the shaft 34 of the timing mechanism to its original or zero position, which produces the ordinary series of stopping operations before described, and brings the extractor basket to rest, and closes switch S₂. Push button switch S₃ is now effective and can be closed to unlock and open the cover.

Further, it is impossible to start the motor while the cover is open, because cover switch S₄ is in the motor starting circuit and is always held open by cam 61 while the cover is open.

Similarly, the motor cannot be started at any time when the brake is applied, because switch S₁ is also in the motor starting circuit and is always open when the brake is applied.

The protruding stem 80 of latch bolt 75 provides for manual release of the cover in the event of emergency, failure of electric current or the supply of fluid pressure.

Further advantages of the invention will be apparent to those skilled in the art.

What I claim is:

1. Apparatus of the character described, comprising a rotatable extracting member, a cover for said member movable to open and closed positions, a fluid pressure operated servomotor for operating said cover, a locking device operatively associated with said servomotor for releasably locking the same in cover closed position, an operator for releasing said locking device, a timing device, manually operated means operatively associated with said operator and controlled by said timing device for causing operation of said servomotor and operator to open the cover, and means whereby said manually operated means is rendered ineffective during the extracting operation.

2. Apparatus of the character described, comprising a rotatable extracting member, brake means for said member, an electric driving motor for said member having an energizing circuit including a main switch, a fluid pressure servomotor operatively connected to said brake means,

and a motor control circuit effective upon the motor and including means for closing and maintaining closed the main switch, said control circuit including switch means actuated by said servomotor and arranged to open the control circuit when the brake means is applied.

3. Apparatus of the character described, comprising a rotatable extracting member, a movable cover therefor, brake means for said member, an electric driving motor for said member having an energizing circuit including a main switch, a fluid pressure servomotor operatively connected to said brake means, a motor control circuit effective upon the motor and including means for closing and maintaining closed the main switch, said control circuit including switch means actuated by said servomotor and arranged to open the control circuit when the brake means is applied, cover operating means, and means actuated thereby for also opening said control circuit when the cover is open.

4. Apparatus of the character described, comprising a rotatable extracting member, a movable cover therefor, brake means for said member, an electric driving motor for said member having an energizing circuit including a main switch, a fluid pressure servomotor operatively connected to said brake means, a motor control circuit effective upon the motor and including means for closing and maintaining closed the main switch, said control circuit including switch means actuated by said servomotor and arranged to open the control circuit when the brake means is applied, cover operating means, means actuated thereby for also opening said control circuit when the cover is open, and manual means controlling the cover operating means and effective only when the brake means is applied.

5. Apparatus of the character described, comprising a rotatable extracting member, a cover for said member movable to open and closed positions, motor means operatively connected to said cover for opening the same, cover locking means operatively connected to and effective upon the motor means to hold the same in cover closed position, brake means for said member, a timing device, means actuated by said timing device for applying the brake means at the conclusion of the extracting period, a single manually operable means, operating connections effective simultaneously on said motor means and said cover locking means, and responsive to operation of said single manually operable means for simultaneously releasing the locking means and cover and energizing the motor means, and operating means between said timing device and manually operable means for rendering the latter ineffective during the extracting operation and effective when said operation is concluded, the brake is applied, and the extracting member comes to rest.

6. Apparatus of the character described, comprising a rotatable extracting member, operating means therefor, a cover for said member movable to open and closed positions, motor means operatively connected to said cover for opening the same, cover locking means, brake means for said member, a timing device, means operated by said timing device and effective upon said operating means for rendering it effective when the extracting operation is begun and upon said brake means for applying the same at the conclusion of the extracting operation, a single manually operable means, operating connections effective simultaneously on said motor

means and said cover locking means, and responsive to operation of said single manually operable means for both releasing the locking means and energizing the motor means, and operating connections between said timing means and manually operable means for rendering the latter ineffective during the extracting operation and effective when said operation is concluded, the brake is applied, and the extracting member comes to rest.

7. Apparatus of the character described, comprising a rotatable extracting member, a cover for said member movable to open and closed positions, a double acting fluid pressure servomotor operatively connected to said cover, means for supplying fluid pressure to one end of said servomotor for opening the cover and to its other end for closing the cover and holding it closed, mechanical locking means operatively connected to and effective upon the servomotor for holding the same and the cover in cover closed position, a timing device, means actuated by said timing device when the extracting operation is concluded and operatively connected to said fluid pressure supply means for evacuating cover clos- 25

5 ing pressure from the servomotor, and manually operated means, operating connections effective upon said fluid pressure supply means, and responsive to operation of said manually operated means for both causing cover opening fluid pressure to be supplied to said servomotor and for causing release operation of said mechanical locking means.
